UNITED STATES PATENT OFFICE.

GEORGE M. HUBBARD, OF NEW HAVEN, CONNECTICUT, ASSIGNOR TO O. B. NORTH & CO., OF SAME PLACE.

BUCKLE.

SPECIFICATION forming part of Letters Patent No. 250,542, dated December 6, 1881.

Application filed October 28, 1881. (No model.)

To all whom it may concern:

Be it known that I, GEORGE M. HUBBARD, of New Haven, in the county of New Haven and State of Connecticut, have invented a new 5 Improvement in Buckles; and I do hereby declare the following, when taken in connection with the accompanying drawings and the letters of reference marked thereon, to be a full, clear, and exact description of the same, and 10 which said drawings constitute part of this specification, and represent, in—

Figure 1, a front view; Fig. 2, a longitudinal section.

This invention relates to an improvement in 15 that class of harness-buckles adapted for the connection of the trace with the tug, and commonly called "trace-buckles," and particularly to that class in which the buckle-frame is provided with a stud to enter the perforation in 20 the trace, with a loop attached to the tug, and through which the trace passes, the said loop tending to hold the trace on the said stud, the object of the invention being to prevent accidental disengagement of the trace from the 25 stud when the draft on the trace is slackened; and the invention consists in the construction, as hereinafter described, and particularly recited in the claim.

A A represent the upper and lower side of 30 the frame; B, the forward bar; C, the rear bar. The usual loop, D, is made upon the upper side, E upon the lower side, and F on the rear part.

H is a central cross-bar, to which a plate, I, is hinged, this plate extending forward over 35 the forward bar, and at a point substantially over the forward bar a stud, a, projects outward from the plate, corresponding substantially to the stud, which is usually made fast to the forward bar, but in this case it is a part 40 of the plate and entirely independent of the bar.

The usual loop is provided for attachment

to the tug, consisting of the two sides L L and front bar, P, to which the tug is attached, the said sides curving outward, so as to pass through the frame and bring the rear bar, R, outside 45 the trace, as seen in Fig. 2, and in the usual manner.

The trace S is introduced inside the rear bar, C, over the hinged plate I, beneath the tug-loop bar R, and then set over the stud a on 50 the plate, as seen in Fig. 2. When the draft upon the trace is slackened the bearing of the tug-loop upon the trace is relieved, as indicated in broken lines, Fig. 2, there being then nothing to prevent the trace from moving outward 55 on the stud; hence it frequently occurs that when the stud is stationary on the frame the trace will slip from its stud and become disengaged. By forming the stud on the hinged plate I, when the draft is slackened the trace 60 naturally throws outward, as before described, but instead of slipping from the stud, as heretofore, the plate I will turn upon the bar, to which it is hinged, outward and follow the trace, as seen in broken lines Fig. 2, because 65 there will be sufficient friction between the stud and the trace to cause the plate so to follow the trace; hence accidental disengagement is prevented.

I claim—

In a trace-buckle, the plate I, hinged to the cross-bar and provided with an outwardly-projecting stud or tongue, the free end of the plate resting upon the end bar of the frame, combined with a tug-loop having its rear bar, 75 R, arranged to press against the outer side of the trace when held between the bar and hinged plate, substantially as described.

GEORGE M. HUBBARD.
